Conrad A. Wittenbach
his Atty.

UNITED STATES PATENT OFFICE.

ALFRED S. WALKER, OF NEW ROCHELLE, NEW YORK.

INDICATOR OR COUNTER.

Application filed January 5, 1924. Serial No. 684,679.

The invention relates to improvements in indicating or counting devices, and the same has for its object to provide a device which may be employed for the purpose of keeping 5 the score in games such as golf, cards, etc. and for counting generally, or for indicating the time at which some act or thing should be done or performed, such as taking or giving medicine, or for fixing the time of a date 10 or engagement.

Another object of the invention is to provide an improved construction of counting or indicating device, which is easy to operate, and in which the indicating member 15 will be held in any position to which the same may be adjusted.

Another object of the invention is to provide an improved construction of counting or indicating device in which the operating 20 parts will not become cramped, caught or wedged during the manipulation thereof.

Another object of the invention is to provide a counting or indicating device in which the indicating means is movable around the 25 edge of the dial or scale.

Another object of the invention is to provide a counting or indicating attachment for a time piece, whereof the dial is employed to serve as a scale with which the attachment 30 cooperates to effect the pointing or to make the indication.

Another object of the invention is to provide an attachment for a time piece which is adapted to be easily attached thereto without 35 injury to said time piece, and which comprises indicating means movable around the dial of the time piece, and utilizes the time notations thereof as a cooperating scale.

Another object of the invention is to provide 40 a compact and simple counting or indicating attachment for a watch, which is not cumbersome, and which when attached to a watch can be carried in the pocket without inconvenience or discomfort.

Another object of the invention is to provide 45 a counting or indicating attachment for a time piece, which is so mounted that it may be easily rotated around the dial of the time piece, and still held under sufficient tension 50 or resistance to rotation as to cause the same to be held to any position to which it may be adjusted.

Other objects of this invention will in part 55 be obvious, and in part be pointed out hereinafter.

To the attainment of the aforesaid objects and ends my invention consists in the novel features of construction, and in the combination, connection and arrangement of parts hereinafter more fully described, and 60 then pointed out in the claims.

In the accompanying drawings showing an illustrative embodiment of the device—

Figure 1 is a plan view illustrating one form of attachment secured in place on a 65 watch, parts being broken away; Figure 1 and the figures hereafter described being on an enlarged scale;

Fig. 2 is a sectional elevation thereof on the line 2—2 of Fig. 1, looking in the direction of the arrow;

Fig. 3 is a side or edge view of the attachment applied to and in position upon a time piece;

Fig. 4 is a perspective view of the attachment;

Fig. 5 is an enlarged detail sectional view thereof on the line 5—5 of Fig. 4, parts being broken away;

Fig. 6 is a detail perspective view of the 80 movable indicating member or ring utilized in the present invention;

Fig. 7 is a side or edge view, with parts broken away and parts in section, of a modified form of the invention in which the attachment comprises two parts pivoted together and capable of receiving and enclosing a watch therebetween, and

Fig. 8 is a sectional view, parts being broken away, of another form of the invention, illustrating the use of a plurality 90 of indicating pointing members or rings.

The embodiments of the invention illustrated in Figs. 1 to 3 and 7 are shown attached to a time piece T such as a clock or 95 watch, the latter being illustrated in the drawing. The indicating or counting device A is shown in place upon the watch T.

The watch as illustrated comprises a dial or face 10 having the usual divisions 11 thereon around or along its edge or outer portions forming unit divisions or minute divisions, five unit divisions forming multiple divisions, the hour divisions which are further designated by the hour numerals 1, 100 2, 3, etc. on the face of the dial, (indicated by the reference numeral 12).

The dial of the time piece or of the counting or indicating device of the present invention, however, may have thereon marks, char- 110

acters or indications in any system of notation capable of being understood. For instance, instead of numerals, letters may be employed, and the divisions or marks may be of any character capable of indicating or representing units, multiples of units, or subdivisions of units. Letters or numerals alone may be employed or mere marks alone or both marks and letters or numerals.

10 The time piece illustrated also comprises the usual hands 13 mounted at 14 for movement by means of the watch mechanism (not illustrated). The watch also comprises the stem 15 having a winding device 16.

15 My improved attachment comprises an annular member 17 having an inwardly extending flange 18, and capable of being placed around the edge or periphery of a watch with the flange 18 extending over the parts of the watch around the dial. In the embodiment of the invention illustrated in Figs. 1 to 5 the lower edge of the annular member 17 is provided with a plurality of spring fingers 19, which when the member 17 is placed upon the watch, engage the under side of the watch and cooperate with the flange 18 to retain said annular member 17 in place upon the watch. The attachment A closely fits the watch, with the flange 18 extending inwardly to points near the crystal, so that the size is not materially increased and the watch can be comfortably carried with the attachment thereon.

30 The annular member 17 also has a recess or notch 20, through which the stem 15 of the watch extends to hold the member 17 upon the watch against rotation, permitting the member 17 to be grasped with one hand, and the indicating means rotated with the other.

35 Interposed between the member 17 and the watch is a pad or cushioning device 21, which consists of a material such as felt, or rubber, to prevent the watch being injured, scratched or damaged when the attachment is applied to or removed therefrom.

40 Mounted below the flange 18 and above the pad 21 is a bearing ring 22 forming with said flange 18 a channel member within which is located an indicating ring or member 23. The ring 23 is provided at its inner edge with an inwardly directed indicating or pointing means 24 riding over the surface of the watch crystal, and also an outwardly extending lug or finger portion 25 whereby to actuate or rotate said ring or member 23 to cause the pointer 24 to be adjusted to any desired indication or mark upon the dial.

45 While I have illustrated a pointer 24, it should be understood that any other suitable indicating means can be employed, such as a notch, a hole or a mark drawn or engraved upon the member 23, and capable of being positioned relative to cooperating marks on the dial to give the desired indication.

Struck up from the member 23 or otherwise mounted thereon, are the spring fingers or tongues 26 which bear against the lower surface of the flange 18, causing a frictional spring resistance between the ring 23 and its bearing or channel formed by the flanges 18 and 22, serving to hold or maintain said ring or member 23 in any position in which it may be adjusted, without unduly resisting the easy manipulation or rotation thereof.

50 The ring 23 has a continuous bearing between the flange 18 and bearing ring 22 whereby it is secured in place upon the attachment, and so supported thereby as to permit of the same being rotated thereon without becoming wedged or cramped. The lug 25 extends outwardly at the inner edge of the ring 23, past the inner edge of the flange 18, and is so located with reference to the indicating device or pointer 24 that, when the lug is engaged to rotate said ring 23, the view of the indicating part or pointer 24 will not be obstructed, that is, the lug 25 is in spaced relation with reference to the indicating device or pointer 24.

55 In Fig. 7 is illustrated a slightly modified form of attachment comprising two members or parts 27, 27^a which are joined together by a spring hinge 28, serving to hold the adjacent edges of said sections 27, 27^a in engagement, and a watch in position intermediate said members 27, 27^a. The member 27 is in the form of an annulus, while the member 27^a is in the form of a shallow receptacle, and the said parts 27, 27^a being so constructed that when closed the same will closely embrace and hold the parts therebetween.

60 In Fig. 8 is illustrated a further modification in which two rotatable rings 23 and 23^a are employed in the attachment or device, the ring 23 being employed to count units, and the other ring 23^a being employed to count multiples of said units. As shown, the rings 23 and 23^a are mounted between the flange 18 and bearing ring 22, one above the other, and are mounted on the annular member 17 to be rotatable independently of each other, each being provided with a pointer 24 or 24^a and with an actuating lug 25 or 25^a, one lug being arranged as not to interfere with the rotation of the other, and the pointers 24 and 24^a being likewise arranged.

65 To use the device (Figs. 1 to 7) the same is held in one hand and the finger portion 25 of the pointing device 23 is engaged by the finger of the other hand and rotated to place the pointer 24 adjacent to the successive marks or divisions, or as desired.

70 When the device is used as an attachment for a time piece, such as a watch, the pointer 24 will serve to indicate units up to 60, there being 60 divisions upon the dial corresponding to the 60 minutes in an hour.

Another use to which the device can be put when attached to a timepiece is that of reminding one of or indicating a time at some act or thing must be done, such as taking medicine. Suppose, for instance that medicine is taken at 9 o'clock, and it is desirable to take the medicine again in four hours, the member 23 is rotated from the position shown (Fig. 1), the pointer 24 being at "9", to position the pointer 24 at "1" as shown in broken lines Fig. 1. When the hands 18 have moved to indicate one o'clock the person can then take the medicine. By means of the construction illustrated in Fig. 8 the score or counting, even when utilizing the dial of a watch or clock, as a scale, can be kept up to higher figures. For instance, while holding the ring 23^a with its indicating device 24^a at which may be taken as a zero value (say at "12" Fig. 1) the other ring 23 may be moved step by step to count up to 60, the number of unit divisions on the face of a watch. Thereupon the ring 23^a may be rotated one unit, each unit movement of ring 23^a representing 60 units. The ring 23 is again rotated through one complete revolution, thereby bringing the number of units counted up to 120. By rotating the ring 23 around the entire circumference and then moving the ring 23^a, one unit for each complete revolution of the ring 23, it will be seen that scoring to a very high figure is possible. Using the time piece dial as the graduated scale, one can count up to 3600.

While I have illustrated the invention as applied to a watch, yet it should be understood that the invention is also applicable to time pieces of various kinds and shapes, and as to features is not even limited for use as an attachment for time pieces, as it can be sold as a complete article with a dial.

While I have designated the number 17 as an "annular member" yet it is to be understood that this member can be of any shape or of a shape corresponding with the shape of the dial or watch which it surrounds. Nor by "annular" do I mean a continuous annular member as illustrated, because the member 17 or the ring 23 may be segmental or semi-annular without departing from the spirit of the invention. Likewise the surface on which the marks or other characters are placed and called herein a "dial" need not be a disk as it can be annular or of various shapes depending on the shape of the watch or of the device; the term "dial" having a broad significance, designating any surface, whether in a watch or not, on which marks or characters can be placed to cooperate with the indicating means of the invention.

As illustrated in Fig. 2 the attachment may have at diametrically opposite points thereon loops 29 (illustrated in broken lines)

whereby an attachment and watch of convenient size may be secured to the wrist of one hand by a strap or chain, the indicator being easily and conveniently operated by the other hand.

Having thus described my said invention, what I claim and desire to secure by Letters Patent is—

1. A device of the character described adapted for attachment to an indicating device, comprising an annular casing having a channel at its inner edge, means for securing said casing to an indicating device, an annular member rotatably disposed within the channel in said casing, a pointer extending inwardly from said annular member, and spring means interposed between said annular member and the wall of said channel for holding said annular member to an adjusted indicating position, substantially as specified.

2. A device of the character described adapted for attachment to an indicating device, comprising an annular casing having a channel at its inner edge, a plurality of spring fingers extending from the periphery of said annular casing for detachably securing said casing to an indicating device, an annular member rotatably disposed within the channel in said casing, a pointer extending inwardly from said annular member, means for actuating said rotatable member, and spring means interposed between said annular member and the wall of said channel for holding said annular member to an adjusted indicating position, substantially as specified.

3. A device of the character described, adapted for attachment to an indicating device including a dial having characters thereon indicating units and multiples of units, said device comprising an annular member having a channel at its inner edge and detachably secured to said indicating device and leaving the dial thereof unobstructed, a plurality of indicating members rotatably mounted upon said annular member within said channel and cooperating with the characters upon said dial, and means for severally actuating said indicating members; one of said indicating members serving to indicate units and the other to indicate multiples of said units, substantially as specified.

4. A device of the character described adapted for attachment to an indicating device including a dial having marks arranged near the edge thereof, said device comprising a member secured around the edge of said dial and comprising opposed circular flanges forming a channel therebetween, a ring rotatable in said channel around said dial and having thereon indicating means cooperating with said marks, spring fingers for causing frictional spring contact between

said member and ring, and means for rotating said ring relatively to said dial, substantially as specified.

5. The combination with a time piece having a dial with marks thereon, of an annular member clipped around the edge of said time piece and having an upper inwardly projecting flange, cushioning means interposed between the time piece and member, 10 a bearing ring below said flange, a ring rotatably mounted between said flange and bearing ring, supported and guided thereby, and having indicating means cooperating with the marks on the dial, and an actuating 15 lug on its inner edge projecting outwardly beyond the member, and spring devices interposed between said rotatable ring and member to frictionally retain the former in each position of adjustment, substantially 20 as specified.

6. The combination with a time piece having a dial with marks thereon, of an annular member embracing the edge of the time piece having a flange extending over the 25 time piece on the side on which the dial is located, spring fingers extending under the opposite side of the time piece, means for retaining the member against rotation on the time piece, a pad interposed between 30 said time piece and member, a ring rotatably mounted on said member below said flange retained in place thereby and having indicating means cooperating with said marks, an actuating lug projecting outwardly from said ring past the inner edge of said flange, and spring means for holding said indicating means in its different positions, 35 substantially as specified.

7. A device of the character described adapted for attachment to an indicating device including a dial having marks thereon arranged therearound and indicating units or multiples of units, said device comprising a member secured around the dial and comprising opposed circular flanges forming 40 a channel therebetween, and a plurality of rings supported within said channel between said dial and said member and independently rotatable thereon around the dial and having indicating means cooperating with 45 the marks on the dial to count units and multiples of units, substantially as specified.

8. A device of the character described adapted for attachment to an indicating device including a dial having characters thereon, indicating units and multiples of units, said device comprising an annular channel member having portions adapted to engage the edges and top of said indicating device, means for detachably securing said channel member about said dial, an annular member rotatably disposed within said channel member between one of said portions and said device, a pointer extending inwardly from said annular member and cooperating with the characters on said dial, and spring means for holding said annular member to adjusted indicating position, substantially as specified. 50 55 60 65 70

Signed at the city of New York, county and State of New York, this 28th day of May, one thousand nine hundred and twenty-three.

ALFRED S. WALKER.
